UNITED STATES PATENT OFFICE.

RALPH S. PEIRCE, OF HINSDALE, ILLINOIS.

SUPPORTING DEVICE.

1,318,584.

Specification of Letters Patent.

Patented Oct. 14, 1919.

Application filed October 11, 1915. Serial No. 55,314.

To all whom it may concern:

Be it known that I, RALPH S. PEIRCE, citizen of the United States, residing at Hinsdale, in the county of DuPage and

5 State of Illinois, have invented a certain new and useful Improvement in Supporting Devices, of which the following is a full, clear, concise, and exact description, reference being had to the accompanying drawings, forming a part of this specification.

My invention relates to supporting devices of the class which employs expandable retaining members for holding bolts, rods or the like in position within openings or 15 recesses formed in wall portions of buildings, or the like. Hitherto it has been the practice to employ sleeves of metal that is softer than the metal of the rods or bolts received in the bores of the sleeves. In some 20 of the devices of the prior art sleeves, together with the portions of the rods threading the same are placed within holes or recesses in the walls or other elements from which the rods are to be projected, where- 25 after the sleeves are upset or crowded into the spaces between the rods and the surrounding parts of the walls rigidly to secure the rods in position. In other devices the sleeves have been expanded into holding 30 relation with the wall portions by means of tools distinct from the rods, the rods being screwed or inserted in position upon the withdrawal of the tools. Lead has been found to be the most suitable material out 35 of which to form the anchoring sleeves but inasmuch as the lead is soft the sleeves are liable to become loose, owing to the inability to maintain the sleeves under sufficient compression.

40 In accordance with my invention I incorporate harder substance with the soft metal of the sleeves, this harder substance being capable of being retained under sufficient compression to enable the sleeves perma- 45 nently to perform their function. The harder material is desirably in the form of small bodies of iron which are distributed throughout the lead sleeves and which contact with each other and also with the lead 50 to receive and retain that degree of compression which is requisite to the maintenance of the firm anchorage of the rods. The lead is a material which is not only ini- 55 tially plastic when it is compressed in ad- justing its relation to the supporting bolt or element, but which also is permanently plas-

tic to enable it and the coarse particles within it jointly to continue to perform their holding function. I also claim these particles with or without the lead.

60 I will explain my invention more fully by reference to the accompanying drawing showing the preferred embodiment thereof and in which Figure 1 is a longitudinal sectional view of an anchoring sleeve made in accordance with the invention; Fig. 2 shows one style of bolt or rod which is anchored in place by means of the sleeve of my invention; Fig. 3 shows another type of rod which may be anchored by the new sleeve; 70 and Fig. 4 is a sectional view on line 4-4 of Fig. 3.

75 Like parts are indicated by similar characters of reference throughout the different figures.

The anchoring sleeve 1 of my invention is desirably formed of molded lead which is indicated at 2. Small pieces 3 of iron or other relatively hard material are molded in the lead to be included in one consistent 80 mass therewith. These pieces 3 may be formed out of waste material such as iron turnings, chips and stampings. In accordance with the preferred method of making the sleeves the iron pieces are loosely and 85 promiscuously located in a mold whereafter the lead is poured into the mold, though I do not wish to be limited to this method of forming the iron and lead in one consistent 90 mass. The lead thus acts as a binder to hold 95 the pieces of iron together, the lead furnishing to the massed pieces of iron the element of compressibility in order that the mass of iron may be reshaped when the sleeve is to be upset or compressed to enable 100 it to anchor the rod that it is to hold in place. In Fig. 2 the rod or supporting element 4 is in the form of a threaded bolt having a head 5 of conical shape. The bore of the anchoring sleeve is threaded by the bolt. 105 The head end of the bolt and the anchoring sleeve 1 are together placed within a cylindrical recess or opening 6 formed in a supporting wall portion 7 whereafter an upsetting sleeve 8 of hard metal such as iron is 110 driven inwardly to crowd or upset the sleeve and effect such a redistribution of the iron particles 4 as to crowd or roll these particles between the rod or bolt and the surrounding portion of the wall, these particles being collectively placed under such compression as to maintain the bolt and wall in firm as-

sembly and rolling to those positions where they may perform their function, although I do not limit myself to this rolling action. After the upset element 8 has been made to 5 perform its function it may be withdrawn or allowed to remain in place, as desired. It will be observed that the iron particles are more crowded at the ends of the sleeve than at the middle of the sleeve whereby exudence 10 of the lead to the rear of the bolt head is prevented, this exudence being a difficulty which was hitherto experienced in connection with lead anchoring sleeves that were unprovided with the iron portions distributed throughout the same.

The supporting device illustrated in Figs. 3 and 4 is of such a construction as may not require the upsetting element 8 inasmuch as the threads upon the rod or bolt 9 are 20 screwed into the sleeve 1 and in being screwed into the sleeve act to upset or compress the same. Some of the particles 3 of iron may be sufficiently large to engage both the support and supporting element at points in a 25 line oblique to the supporting element and extending obliquely across the gap between some of the threads and the surrounding portion of the wall, thus serving as compression members in a truss formation, these 30 larger portions of iron then operating independently of the lead and independently of their companions in firmly gripping the wall and rod and holding them in fixed relation. This direct coöperation of the iron 35 portions with the rod and the surrounding wall is not indispensable to the firm anchorage of the rod, since it is apparent that the iron portions may coöperate with each other and also with the lead in effectively 40 holding the rod and wall in fixed relation.

While I have herein shown and particularly described the preferred embodiment of my invention I do not wish to be limited to the precise details of construction shown 45 as changes may readily be made without departing from the spirit of my invention but having thus described my invention I claim as new and desire to secure by Letters Patent the following:—

50 1. The combination with a supporting element; of an anchoring element for holding the supporting element and formed of soft permanently plastic material and small

bodies of hard material molded in the soft material; and a support having an opening 55 receiving said supporting element and anchoring element and engaged by the anchoring element which is crowded between the support and the supporting element to bring the small anchoring elements into firm holding 60 relation with said supporting element and the support.

2. The combination with a supporting element; of an anchoring element for holding the supporting element and formed of soft 65 permanently plastic material and small bodies of hard material molded in the soft material and having the soft material interposed between the same; and a support having an opening receiving said supporting 70 element and anchoring element and engaged by the anchoring element which is crowded between the support and the supporting element to bring the anchoring element into firm holding relation with said supporting 75 element and the support.

3. The combination with a supporting element; of a support with a recess therein in which said supporting element is received; and an anchoring element within the recess 80 and engaging said support and supporting element, this anchoring element being in the form of a hollow sleeve composed of soft metal with particles of hard metal embedded therein, said hard particles being collectively 85 under compression, to maintain the support and supporting element in firm assembly.

4. The combination with a supporting element; of a support with a recess therein in which said supporting element is received; 90 and an anchoring element within the recess and engaging said support and supporting element, this anchoring element being in the form of a mass of soft metal with particles of hard metal embedded therein, 95 said hard particles being collectively under compression, to maintain the supporting element and support in firm assembly.

In witness whereof I hereunto subscribe my name this seventh day of October, A. D. 1915.

RALPH S. PEIRCE.
